UNITED STATES PATENT OFFICE.

ALONZO J. SIMMONS, OF LOS ANGELES, CALIFORNIA.

MEANS FOR PREVENTING AND REMOVING INCRUSTATION FROM BOILERS.

No. 867,430.

Specification of Letters Patent:

Patented Oct. 1, 1907.

Application filed October 25, 1906. Serial No. 340,569.

To all whom it may concern:

Be it known that I, ALONZO J. SIMMONS, a citizen of the United States, residing at Los Angeles, in the county of Los Angeles and State of California, have 5 invented certain new and useful Improvements in Means for Preventing and Removing Incrustations from Boilers, of which the following is a specification.

This invention relates to means for preventing and removing incrustation from boilers.

10 One object is to dispose in the means for conveying feed water to a boiler a suitable chamber provided with one or more movable incrustation preventive balls.

Another object resides in the provision of means for 15 preventing and removing incrustation from boilers embodying such characteristics that by a centrifugal or whirling action there is imparted to the water one or more chemical agents capable of accomplishing the purposes set forth.

20 A still further object of the invention is to provide an apparatus constructed and arranged to deliver water to the boiler from any suitable source and associate with the apparatus a chamber provided with a race-way for a whirling action of the water and of balls 25 therein under velocity pressure and in their flight give to the water the agent or agents calculated to prevent and remove incrustation from boilers.

It is still further designed to provide means for preventing and removing incrustation from boilers embodying such characteristics that an incrustation preventive body or bodies may be arranged for movement 30 under the influence of the feed water to continuously present particles thereof to the water.

With the above and other objects in view the present 35 invention consists in the combination and arrangement of parts hereinafter more particularly referred to, shown in the accompanying drawings, and particularly pointed out in the appended claims, it being understood that changes may be made in the form, proportion, size and minor details without departing from the spirit or scope of the invention or sacrificing any 40 of the advantages thereof.

In the drawings:—Figure 1 is a side elevation of the invention; Fig. 2 is a horizontal sectional view thereof; Fig. 3 is a transverse, vertical, sectional view of the mixing chamber; Fig. 4 is a sectional view of one form of incrustation preventive ball; and Fig. 5 is a sectional view of another incrustation destroyer and preventive ball provided with numerous perforations 45 and also showing a shield used when filling the ball with chemicals. Fig. 6 is a sectional view of a third form of incrustation preventive ball.

Referring now more particularly to the accompanying drawings, the reference character 1 indicates a 50 pump of any suitable variety provided with an inlet pipe, 2 leading from any suitable source and an outlet

3 connecting with the neck 4 of the mixing chamber 5 and secured thereto in any suitable manner, the mixing chamber 5 communicating with the boiler 6 by way of the pipe 7.

60 The mixing chamber 5 is preferably circular in form, although it may be of any other shape, and is provided with inner and outer walls 8 and 9, respectively, to form a race-way for the guidance of the balls 11 whirled continuously through the race-way by the water under pressure from said pump or other source. Thus it will be understood that the water and balls travel rapidly through the race-way, and in operation it will be seen that part of the water in its whirl through the race-way falls behind the balls 11 and passes through the V-shaped or other form of slot 12 and into the pocket 13 to the boiler by way of the aforesaid boiler connecting pipe 7.

70 The water fed into the boiler by my improved apparatus is sometimes heavily charged with impurities, but be that as it may, I have found that by using certain chemicals the water may be so treated as to overcome the formation of incrustation or other scale upon the interior of the boiler. I have also found that my invention will satisfactorily remove from boilers any 75 incrustation or scale formed thereupon prior to the use of my apparatus. To accomplish such results the chemicals should be thoroughly intermingled with the water and to insure this thorough intermingling of the chemicals and water I form the balls 11 hollow that 80 they may be adapted to carry the chemicals, and I provide each ball with a perforation 14 through which chemicals may be inserted and through which the chemicals may be discharged from the ball due to the 85 centrifugal action of the balls in operation. In one 90 embodiment of my invention, I employ a composition consisting of hemlock extract and soda-ash with or without water. These chemicals are thoroughly mixed with the water and in a semi-liquid or paste state; the composition thus compounded is inserted into the ball 95 11 through the perforation 14 and allowed to dry and harden. When the balls are ready for use, that is, after the compound has been hardened by heating them or in any other suitable manner, the balls are inserted in the mixing chamber 5 through the opening 15 100 105 which is normally closed by the cap 16.

The water whirling the balls around the race-way of the mixing chamber causes the centrifugal action of the balls to slowly give out the chemicals contained therein, the water in its passage through the race way of course 110 entering the opening 14 and softening the hardened compound within the balls. The openings 14 are of small size to permit a slow discharge of the chemicals.

I do not limit myself to the nature of chemicals employed, for in addition to the above mentioned compound, I might employ bicarbonate of soda, Glauber's salt, sal-soda, common salt and potash; or red lead, lin-

seed oil and coal tar; or I might employ silica sand, carbonated soda-ash and Irish moss with or without water; or I might employ graphite and tannic acid with or without water. It will thus be seen that I am not limiting myself to the chemicals used but that in this particular case I am claiming the apparatus employed in carrying out the objects of my invention. In practice, the shells or balls are formed, preferably of thin, soft metal, iron preferred, and by reason of frictional engagement of the shells or balls with the walls of the mixing chamber, small particles of iron are given off from the shells or balls and taken up by the water to intermingle with the chemicals discharged from the balls, although, of course, the above mentioned separate sets of chemicals combined in the manner stated will effect the desired results. If preferred, I might provide a ball or other body *a* shown in Fig. 6 composed of any one of the above or other compounds in combination with small particles of iron, the whole ball in time wearing away, necessitating insertion in the mixing chamber of new balls. In this last compound, the ingredients might be molded, pressed or otherwise forced into intimate contact with one another to provide a comparatively hard but brittle ball. Further, I might add New Orleans molasses or flour or both to any one of the above compounds, especially to the last named compound.

In Fig. 5 I illustrate a chemical carrying ball 17 provided with numerous perforations 18. This ball performs the same functions set forth for the ball 11, and in order to facilitate filling of the ball 17 I may employ a cup shaped support 19.

The operation of the invention will now be stated briefly as follows:—Water under pressure is forced into the mixing chamber 5 where it is whirled around in the chamber to move the balls rapidly therethrough and to cause the balls to give off such proportions of chemicals to intermingle with the water passing through the pipe 7 into the boiler 6 to positively prevent or remove incrustation formed upon the walls of the boiler.

What is claimed is:—

1. The combination with a boiler feed pipe; of an incrustation preventive body movably arranged in the path of water passing through the feed pipe.
- 45 2. A mixing chamber provided with a race-way and a

ball arranged to travel in the race-way under pressure, the ball carrying a chemical compound.

3. A mixing chamber provided with a race-way, and a series of balls arranged to travel in the race-way under pressure, each ball carrying a chemical compound. 50

4. A mixing chamber, and an incrustation preventive ball arranged for movement in the chamber.

5. The combination with a boiler feed pipe; of an incrustation preventive bodies movably arranged in the path of water passing through the feed pipe. 55

6. The combination with a boiler feed pipe; of an incrustation preventive body movably arranged in the path of water for continuous movement by the water passing through the feed pipe.

7. The combination with a boiler feed pipe; of a series of incrustation preventive bodies movably arranged in the path of water for continuous movement by the water passing through the feed pipe. 60

8. The combination with a boiler feed pipe; of a chamber disposed in the line of the feed pipe; and an incrustation preventive body disposed in the chamber for whirling action therein under pressure of the water passing through the pipe and chamber. 65

9. In combination with a boiler and a pump; of a chamber arranged between the pump and boiler, and an incrustation preventive ball movable in said chamber. 70

10. In combination with a boiler and a pump; of a chamber arranged between the pump and boiler, and chemical carrying balls arranged to move in said chamber.

11. The combination with a boiler feed pipe; of a chamber disposed in the line of the feed pipe; and a series of incrustation preventive bodies disposed in the chamber for whirling action therein under the pressure of water passing through the pipe and chamber. 75

12. The combination with a boiler feed pipe; of an incrustation preventive body arranged in the path of water passing through the pipe for disintegration within said pipe. 80

13. The combination with a boiler feed pipe; of a race-way arranged in the pipe, and an incrustation preventive body adapted to travel in the race-way. 85

14. The combination with a boiler feed pipe; of a race-way arranged in the pipe and an incrustation preventive body arranged for continuous travel in the race-way under the pressure of water passing through the pipe. 90

15. The combination with a boiler feed pipe; of an incrustation preventive body arranged for movement in the feed pipe, and means constructed and arranged in the pipe to limit the movement of the body.

In testimony whereof I have signed my name to this specification in the presence of two subscribing witnesses. 95
